US00D661707S

(12) **United States Design Patent**
Akana et al.

(10) **Patent No.:** US D661,707 S
(45) **Date of Patent:** ** Jun. 12, 2012

(54) **DISPLAY MODULE FOR AN ELECTRONIC DEVICE**

(75) Inventors: **Jody Akana**, San Francisco, CA (US); **Bartley K. Andre**, Menlo Park, CA (US); **Joshua D. Banko**, Palo Alto, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Stephen McClure**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **John P. Ternus**, Redwood City, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/376,057**

(22) Filed: **Sep. 30, 2010**

(51) **LOC (9) Cl.** **14-03**

(52) **U.S. Cl.** **D14/496; D14/203.3**

(58) **Field of Classification Search** ..... **D14/496, D14/401, 435, 474, 483, 217, 137, 138, 160, D14/168, 356, 203.1–203.8, 507; 345/156, 345/169, 173–179, 905; 715/727–729, 864; 710/1, 5, 8; 713/1, 600; 455/1.1, 1.7, 73, 455/344–347, 93, 95, 3.01–3.06, 550.1, 573.1; 370/342–344; 369/1, 2, 6–12; 463/43–47; 273/148 B**

(57) **CLAIM**

The ornamental design for a display module for an electronic device, as shown and described.

DESCRIPTION

FIG. 1 is a front perspective view of a display module for an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The shade lines in the Figures show transparency.
